COMBINATION CONTAINER AND DISPENSER

Louis A. Trevisan, Bloomfield, N. J., assignor to
 American Can Company, New York, N. Y., a
 corporation of New Jersey

Application December 9, 1939, Serial No. 308,473

1 Claim. (Cl. 299—24)

The present invention relates to a combination storing and dispensing device and has particular reference to an improved unitary demothing package adapted to contain dichloricide crystals which vaporize when exposed to atmosphere.

An object of the present invention is the provision of a moth preventive vapor disseminating device which includes a sealed container for holding chemical crystals for shipment and storage and which when opened and used as a disseminating device confines the crystals in a perforated receptacle part while permitting the escape and dissemination of the vapor element.

Another object of the invention is the provision of a gas-proof container for the preservation of chemical crystals during storage and distribution, which may be opened for instant use and converted into a disseminating device for generating moth preventive and destructive vapors by the attachment of a supplemental perforated receptacle which receives the crystals and holds the same while disseminating the vapors.

Yet another object of the invention is the provision of a drum head sealed container for packaging and distributing chemical crystals, which container may be converted easily into a vapor disseminating device by the breaking open of the drum head and by the attachment to the opened container of a supplemental perforated receptacle, thereby permitting the device to be hung upon a wall or support while the crystals vaporize and permeate the surrounding atmosphere to exterminate moths and to destroy moth eggs and larvae.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a unitary package or vapor disseminating device embodying the present invention;

Fig. 2 is an enlarged fragmentary perspective view illustrating a preferred embodiment of the device with parts broken away and with parts in section showing a supplemental receptacle affixed to a filled distributing container;

Fig. 3 is a fragmentary view in section of parts of a closed friction top can adapted for use as the distributing container element of a modified construction; and

Fig. 4 is a fragmentary view in section of the modified form of vapor disseminating device illustrating a supplemental receptacle part insert-

ed into the opened distributing container of Fig. 3.

Referring to the drawing, Figs. 1 and 2 illustrate a preferred embodiment of the present invention and show as a part of a vapor disseminating device, a storage and distributing container 11. This container is fully described in the W. M. Holloway, United States Patent 1,980,995, issued November 20, 1934.

10 The container 11 comprises a cylindrical sheet metal body 12, closed by a bottom end 13 double seamed to the body in an end joint 14. The opposite end of the container is provided with an outwardly extending stop bead 15. A wall 16 at one side of the stop bead merges into a friction wall 17 extending parallel to but spaced from the body. This friction wall joins into a wall 18 which merges into the upper cylindrical wall section of the container as at 19.

20 A frangible seal or drum head 21, preferably of a cellulose material which is impervious to both gas and air, has an outer edge 22 incorporated in and secured to the upper part of the container wall. The upper edge of the wall 19 is 25 curled inwardly at 23 to provide this joint and the impervious drum head thus makes a suitable seal to prevent deterioration of the chemical demothing crystals, designated by the numeral 24 which are sealed in the container.

20 A series of interrupted threads 25 are formed in the body by being outwardly pressed in the wall 19, intermediate the friction wall 17 and the curled edge 23 of the container. The threads 25 extend a relatively short distance around the circumference of the can body, each thread arranged at an angle relative to the upper curl edge 23.

An outer screw closure may be provided to cover and protect the drum head 21 at the upper 40 end of the container body under conditions of distribution and storage. Such a closure if used would be threadedly secured to the container by utilizing the threads 25 of the body.

A supplemental receptacle 26 is a necessary 45 part of the disseminating device and since this serves the same protection as a separate screw cover for the distributing container, the screw cover will preferably be eliminated. The receptacle 26 therefore is affixed to the container 11 and both parts are distributed as a unitary package to the ultimate consumer.

The consumer's first step, in preparing the disseminating device for use, is the removal of the cover if an outer screw closure is present or 55 the removal of the supplemental receptacle 26

when such a receptacle is a part of the package. The next step is to break and remove the frangible seal 21, from the sealed container 11 thus opening the sealed container. The supplemental receptacle 26 is next secured to the crystal containing or distributing container 11 into its disseminating position. The unit is then inverted into the position of Fig. 1, the crystals 24 falling out of the container 11 and into the receptacle 26 until the latter is filled. The device is now ready for use and as the crystals vaporize and thus become smaller other crystals from the container above drop down and maintain the supplemental receptacle filled.

Receptacle 26 comprises a metal cylindrical body 27 which is perforated at 28 to provide a plurality of openings extending throughout its surface. This body 27 is secured to a flanged connection 29 (Fig. 2) by a double seam joint 31 at the opposite end, the body is double seamed to a perforated end member 32 in an end seam joint 33.

Figure 2 of the drawing shows the supplemental receptacle 26 as being affixed to the filled distributing container 11 at the time the container and receptacle are first received by the ultimate consumer. Such an attachment is made by the interengagement of the interrupted can body threads 25 with similar threads 34 formed in the connection 29. The threads 34 are also at an angle relative to the edge of the connection and are pressed inwardly at spaced intervals in a flange wall 35 of the connection 29.

In order to conveniently hold the disseminating device in its inverted position (Fig. 1) provision is made for hanging it up. A suitable fastener 36 is secured to the end member 13 by means of a rivet 37. Such a fastener may be a flat plate resting directly on the end member, as illustrated by a dotted outlined portion 38 when the container is being stored or distributed. An aperture 39 is formed in the fastener 36 and when the unit is to be hung up for disseminating the vapors, such a plate may be bent up at right angles and shifted on its connection into the full line position of Fig. 1. A nail or screw on the wall may then be passed through the opening 39 and slid into a slotted extension 41 having a width too small for the passage therethrough of the nail head. This prevents the device from becoming detached from its support. Such a device may be hung conveniently upon a closet wall, door or shelf where vaporization of the chemical crystals will be desirable.

Figures 3 and 4 of the drawing show a modified form wherein a friction top closure can 42 is used as a distributing container. A container body 43 has secured to one end thereof a friction ring 44 as by an end seam joint 45. The container 42 is closed by a usual type of friction plug closure 46 (Fig. 3) which is inserted into the ring member 44 to seal the container for preserving the chemical crystal contents.

Upon removal of the closure 46 from its sealed position the container is ready to be converted into a disseminating device. This is done by the

insertion of one end of a supplemental receptacle 47 (Fig. 4) into the friction ring 44.

The supplemental receptacle 47 (Fig. 4) is similar to receptacle 26 (Fig. 2) and includes a tubular body wall 48 which is also perforated, as at 28, to provide a plurality of openings extending throughout the cylindrical surface. One end of the supplemental receptacle 47 is closed by a perforated end member 49 which is secured to the tubular body 48 by a usual type end seam joint 51.

The end of the supplemental receptacle 47 which engages with the container 42 is open and the edge of the body wall 48 at this end is curled inwardly as at 52. An annular outwardly pressed bead 53 is formed adjacent the curled edge 52 and provides a shoulder 54 or stop on the outer surface of the body wall 48. This limits the degree of insertion of the receptacle into the friction ring 44. The outer annular surface of the receptacle wall which is located between the curled edge 52 and the shoulder 54, designated by the numeral 55, is preferably sized to provide a snug friction fit within the ring 44 of the distributing container 42 (Fig. 4). This holds the supplemental receptacle 47 in proper cooperating position with the container 42 so that it will receive the crystals from the container after the device is inverted for use. Thus the two connected parts of the package provide a unitary insecticide vapor disseminating device.

A similar tab member 36, as illustrated in Fig. 1, may be used to hang up the inverted device and may be secured to the bottom end of the container 42 in the same manner.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A storing and disseminating device for chemical crystals, comprising an imperforate open ended distributing container for holding said crystals, said open end of the container being sealed by a frangible sheet to preserve the chemical contents, and a supplemental perforated receptacle having an open end in threaded engagement with the open end of the container and over said sealing sheet, said frangible sealing sheet being adapted to be broken out when said container and receptacle are separated to open the container, whereby reassembly of the said receptacle upon the thus opened container produces a vapor disseminating device permitting a supply of crystals to pass into and fill said receptacle when the latter is placed below said container in inverted position, and instrumentalities on the opposite end of said container for supporting said device in its inverted position so that the crystals will vaporize and disseminate through said perforations.

LOUIS A. TREVISAN.
